CIRCUIT INTERRUPTER

Leon R. Ludwig, Snyder, N. Y., and Winthrop M. Leeds, Pittsburgh, and Benjamin P. Baker, Turtle Creek, Pa., and James M. Cumming, deceased, late of Monroeville, Pa., by Helen J. Cumming, executrix, Monroeville, Pa., assignors to Westinghouse Electric Corporation, East Pittsburgh, Pa., a corporation of Pennsylvania

Application June 29, 1950, Serial No. 171,158

9 Claims. (Cl. 200—150)

1

This invention relates to circuit interrupters in general, and, more particularly, to arc-extinguishing structures for circuit interrupters of the liquid-break type.

A general object of our invention is to provide an improved liquid-break type of circuit interrupter which will more effectively interrupt the circuit therethrough than has heretofore been attained.

Another object is to provide an improved liquid-break circuit interrupter in which an improved piston construction is employed to more effectively drive liquid through the arc to extinguish the same.

A more specific object is to provide an improved circuit interrupter of the type specified in the immediately preceding paragraph in which the arc is drawn along the central vertical axis of the interrupter, and in which the design is symmetrical with no unbalanced horizontal mechanical forces.

Still another object is to provide an improved piston construction for a liquid-break type of circuit interrupter in which improved time-delay means are provided before application of the liquid to the arc.

Another object is to provide an improved differential piston construction of the liquid break type.

Further objects and advantages will readily become apparent upon reading the following specification taken in conjunction with the drawings, in which:

Figure 1 is a side elevational view, partially in vertical section, of a tank-type liquid-break circuit interrupter employing our invention and shown in the closed-circuit position;

Fig. 2 is an enlarged vertical sectional view through the left-hand arc-extinguishing unit of Fig. 1, the contact structure being shown in the closed-circuit position;

Fig. 3 is a view similar to that of Fig. 2, but showing the disposition of the contact structure at an intermediate point in the opening operation during the interruption of high-amperage currents;

Fig. 4 is a sectional view taken along the line IV—IV of Fig. 2;

Fig. 5 is a view similar to Fig. 2, but showing a modified form of our invention, the contact structure being shown in the closed-circuit position;

Fig. 6 is a view similar to that of Fig. 5, but showing the disposition of the contact structure at an intermediate point in the opening opera-

2

tion during the interruption of high amperage currents;

Fig. 7 is a sectional view taken along the line VII—VII of Fig. 5;

5 Fig. 8 illustrates still another form of our invention, the contact structure being shown in the closed-circuit position;

Fig. 9 is a view similar to that of Fig. 8 but indicating the partially open-circuit position of 10 the contact structure, and

Fig. 10 is a sectional view taken along the line X—X of Fig. 8.

Referring to the drawings, and more particularly to Fig. 1 thereof, the reference character

15 1 designates a tank filled to the level 2 with a suitable arc-extinguishing liquid, in this instance circuit breaker oil. Depending from the cover 3 of the tank 1 are a pair of terminal bushings 4, 5, to the lower ends of which are secured 20 identical arc-extinguishing units, generally designated by the reference numeral 6. Electrically interconnecting the units 6 in the closed circuit position, shown by the full lines in Fig. 1, is a conducting cross-bar 7 actuated vertically by an 25 insulating lift rod 8, and having at its opposed extremities rod-shaped movable contacts 9.

Referring to Figs. 2—4, which more clearly show the internal construction of the arc-extinguishing units 6, it will be apparent that we have provided an elongated insulating casing 10 having an internally disposed insulating sleeve 11, the latter having an enlarged portion 12 and a restricted portion 13. An apertured partition plate 14 is disposed upon an internally provided flange 15 of the casing 10. The aperture 16 provided in the partition plate 14 accommodates longitudinal travel of a movable contact assembly, generally designated by the reference character 17, and including an intermediate contact 18, a hollow piston member 19 and a driving piston 20.

35 It will be noted that in the closed circuit position, shown in Fig. 2, the movable contact 9 engages the intermediate contact 18, the latter in turn engaging a relatively stationary contact 21, 45 which is preferably resiliently mounted by means of a stem 22 and a compression spring 23. A shunt 24 electrically connects the stem 22 with the apertured cover plate 25 of the unit 6. The cover plate 25 may be suitably secured by a clamp 26 (Fig. 1) to the lower end of the terminal bushings 4, 5.

The hollow piston member 19 consists of a plurality of apertured insulating plates 27, 28 having different internal diameters. Preferably, insulating tie rods 29 (Fig. 4) are provided to se-

cure the plates 27, 28 to the plate portion 30 of the movable contact assembly 17.

We provide biasing means 31, in this instance including a compression spring 32, biasing the driving piston 20, and hence the entire movable contact assembly 17 to the open circuit position. Valve means 33 are provided to permit oil to leave the chamber 34 in back of the piston 20 during the closing operation. Such valve means preferably includes a valve sleeve 35 picked up by a flange 36 secured to and movable with the movable contact 9. Apertures 37 are provided in the piston 20 to permit the exit of oil out of the chamber 34 during the closing stroke.

The opening operation of this form of our invention will now be described. In the closed circuit position of the interrupter, shown in Figs. 1 and 2, the electrical circuit therethrough includes terminal bushing 4, conducting cap 25, flexible shunt 24, relatively stationary contact 21, intermediate contact 18, lower movable contact 9 and through the conducting cross-bar 7 to the right-hand unit 6. The circuit extends through the right-hand unit 6 in the same manner previously described to the right-hand terminal bushing 5.

During the opening operation, suitable mechanism, not shown, either responsive to manual operation or to the existence of overload conditions existing in the electrical circuit controlled by the interrupter, operates to cause downward opening movement of the lift rod 8. The downward motion of lift rod 8 carries with it the two movable contacts 9. Considering only the left-hand unit 6, it will be apparent that the compression spring 32 forces the driving piston 20 and the entire movable contact assembly 17 downwardly, drawing an arc 38 more clearly shown in Fig. 3. Since the valve 33 is open, the assembly 17 moves downwardly freely until the piston member 19 enters the restricted portion 13, at which time oil is forced through the inlet passages 39 and against the arc 38 and upwardly through the interior 40 of the hollow piston member 19. Since the movable contact assembly 17 slows up after the piston member 19 enters the restriction 13, the movable contact 9 will separate from the intermediate contact 18 to draw a second serially related arc 41, more clearly shown in Fig. 3.

During the interruption of heavy currents, the pressure generated by the arc 41 within the piston chamber 34 will be high, closing the valve 33 and assisting the compression spring 32 in driving the piston 20 downwardly, as shown in Fig. 3. During the interruption of light currents, where the pressure generated by the arc 41 is negligible, dependence must be had upon the compression spring 32 alone to bring about the necessary downward opening motion of the movable contact assembly 17.

The upward flow of oil indicated by the arrows in Fig. 3 through the interior 40 of the piston member 19 causes extinction of the arc 38 and hence circuit interruption. In the fully open circuit position, the lower movable contact 9 is withdrawn out of the piston member 20 to an open circuit disconnect position indicated by the dotted lines 42 of Fig. 1.

During the closing operation, the lift rod 8, cross-bar 7 and movable contacts 9 move upwardly. The contact 9 enters the valve means 33 of the piston 20 and causes engagement between the flange 36 and the valve sleeve 35, thereby opening the valve means 33.

The movable contact 9 strikes the intermediate contact 18 and moves the intermediate contact 18, and hence the assembly 17, upwardly until engagement is made between relatively stationary contact 21 and intermediate contact 18, the compression spring 23 providing the requisite contact pressure. The circuit is then closed.

Figs. 5-7 illustrate another embodiment of our invention. In this embodiment, the modified unit 44 has an intermediate contact 45 connected by a lost-motion connection 46 with the movable contact assembly 17. In this form of our invention, the piston member 19 moves along vertical walls provided by an insulating sleeve 47 disposed interiorly of the casing 10.

The operation is as follows. During the opening operation, the downward opening movement of the contact 9 immediately permits fast downward opening motion of the intermediate contact 45 relative to the movable contact assembly 17 because of lost-motion mechanical connection 46 therebetween. The intermediate contact 45 is biased downwardly by a compression spring 49 to a stop 50 on the connecting sleeve 51. Since the intermediate contact 45 is comparatively light, the arc 38 (Fig. 6) will be very rapidly formed. The intermediate contact 45 will soon come to its stop 50 and thereafter will move with the assembly 17. Thus the first few inches of arc length 38 are very rapidly formed. The movable contact assembly 17 will be driven downwardly by the driving piston 20 under the influence of the compression spring 32. The downward motion of the contact assembly 17 forces oil within the region 48 through the inlet passages 39 and upwardly into the interior 40 of the hollow piston member 19 against the arc 38. Because of the relatively slow downward travel of the assembly 17, the lower movable contact 9 will separate from the lower contact portion 52 of the intermediate contact 45 to establish the arc 41, as shown in Fig. 6.

As before, during high current interruption, the pressure generated by the arc 41 within the piston chamber 34 will be high, closing the valve means 33 and assisting the compression spring 32 in driving the driving piston 20 downwardly. This condition is shown in Fig. 6. During low current interruption, on the other hand, the pressure formed at the arc 41 will be small, and the valve means 33 will remain open so that oil may be drawn through the apertures 37 into the region 34.

The upward flow of oil through the hollow piston member 19 quickly extinguishes the arc 38 and the circuit is interrupted. As before, the movable contact 9 is withdrawn to the disconnect piston shown by the dotted lines 42 of Fig. 1.

Figs. 8-10 illustrate a third embodiment of our invention utilizing a differential piston construction in the modified unit 53. In this embodiment, the casing 10 has the sleeve 41 constructed, as before, with the enlarged portion 12 and the restricted portion 13. The differential piston member, generally designated by the reference character 54, includes a hollow piston member 19 and two piston surfaces 55 and 56. Since the area of the piston surface 56 is larger than the area of the piston surface 55, the piston member 54 will move downwardly, thereby forcing oil out of the region 58, through inlet passages 59 and downwardly through the interior 40 of the hollow piston member 19. The com-

pression spring 32, as before, assists downward motion of the driving piston 20.

In this embodiment, we have only a single arc 60 being drawn by cooperation of the contacts 21, 9. If the pressure generated by the arc 60 is small, reliance is largely had upon the biasing action exerted by the compression spring 32. If the current being interrupted is high, the arc 60 will generate a high pressure which will act upon the two surfaces 55, 56. Because of their unequal areas, the pressure will have a net effect in forcing the differential piston assembly 54 downwardly, thereby causing oil to travel from the region 59 through the inlet passages 58, and through the interior 40 of the piston member 19 to the region 34 in back of the lower piston 20. This condition is shown in Fig. 9.

The foregoing description of three embodiments of our invention shows how we have provided an improved liquid break type of circuit interrupter utilizing novel piston constructions for bringing about effective circuit interruption. During the interruption of relatively light currents, dependence is placed upon the compression spring 32 in effecting downward opening motion of the contact assemblies 17 or the differential piston assembly 54. During high current interruption, the pressure generated will assist the compression spring 32 in either forcing the driving piston 20 of Figs. 2 and 5 downwardly, or else forcing the differential piston 54 downwardly, thereby assisting the compression spring 32.

It will be noted that the oil flow through the interior 40 of the hollow piston member 19 is effective in extinguishing the arc 38 or 60. The interior 40 is corrugated to minimize breakdown longitudinally of the piston 19 due to carbonization of the insulating surfaces.

Although we have shown and described specific structures, it is to be clearly understood that the same were merely for the purpose of illustration, and that changes and modifications may readily be made therein by those skilled in the art without departing from the spirit and scope 45 of the appended claims.

We claim as our invention:

1. A circuit interrupter of the liquid break type including a casing, a rod-shaped relatively stationary contact disposed adjacent one end of the casing, a movable contact assembly movable within the casing including a hollow piston member through which liquid may flow, an intermediate contact and a driving piston, the intermediate contact being cooperable with the relatively stationary contact to establish an arc which is subjected to the liquid flow passing through the hollow piston, a movable contact movable adjacent the other end of the casing and cooperable with the intermediate contact to establish a second serially related arc, the rod-shaped relatively stationary contact protruding at least part way through the hollow piston member to engage the intermediate contact in the closed circuit position of the interrupter, liquid inlet passage means disposed in the movable contact assembly adjacent the point of engagement of the stationary and intermediate contacts, means biasing the movable contact assembly to the open circuit position, and the second serially related arc assisting opening motion of the driving piston during high current interruption.

2. A circuit interrupter of the liquid break type including a casing, a rod-shaped relatively

stationary contact disposed adjacent one end of the casing, a movable contact assembly movable within the casing including a hollow piston member through which liquid may flow, an intermediate contact and a driving piston, the intermediate contact being cooperable with the relatively stationary contact to establish an arc, a movable contact movable adjacent the other end of the casing and cooperable with the intermediate contact to establish a second serially related arc, the rod-shaped relatively stationary contact protruding through the hollow piston member to engage the intermediate contact in the closed circuit position of the interrupter, liquid inlet passage means disposed in the movable contact assembly adjacent the point of engagement of the stationary and intermediate contacts, means biasing the movable contact assembly to the open circuit position, the second serially related arc assisting opening motion of the driving piston during high current interruption, the casing having a widened portion and a restricted portion, and the hollow piston moving from the widened portion into the restricted portion to thereby provide a time delay before application of liquid to the first said arc.

3. A circuit interrupter of the liquid break type including a casing having an apertured partition member, a relatively stationary rod-shaped contact disposed adjacent one end of the casing, the casing on one side of the apertured partition member having an enlarged portion and a relatively restricted portion, a movable contact assembly movable through the aperture in the partition member and including a hollow piston member through which liquid may flow, an intermediate contact and a driving piston, the rod-shaped stationary contact extending through the hollow piston member to engage the intermediate contact in the closed circuit position of the interrupter, a rod-shaped movable contact movable through the driving piston to engage the intermediate contact in the closed circuit position, the relatively stationary contact and the intermediate contact being cooperable to establish an arc within the hollow piston member, the movable contact being cooperable with the intermediate contact to establish a second serially related arc, the hollow piston member moving from the enlarged portion of the casing to the restricted portion thereof, inlet passage means provided in the contact assembly adjacent the point of engagement of the stationary and intermediate contacts, the driving piston being disposed on the other side of the partition member, means biasing the movable contact assembly to the open circuit position, and the said second arc assisting the driving piston during high current interruption.

4. A circuit interrupter of the liquid break type including a casing, a rod-shaped relatively stationary contact disposed adjacent one end of the casing, a movable contact assembly movable within the casing including a hollow piston member through which liquid may flow, an intermediate contact and a driving piston, the intermediate contact being cooperable with the relatively stationary contact to establish an arc which is subjected to the liquid flow passing through the hollow piston, a movable contact movable adjacent the other end of the casing and cooperable with the intermediate contact to establish a second serially related arc, the rod-shaped relatively stationary contact protruding through the hollow piston member to engage the intermediate contact in the closed circuit position of the interrupter, liquid inlet passage means disposed in the movable contact assembly adjacent the point of engagement of the stationary and intermediate contacts, means biasing the movable contact assembly to the open circuit position, and the second serially related arc assisting opening motion of the driving piston during high current interruption.

intermediate contact in the closed circuit position of the interrupter, liquid inlet passage means disposed in the movable contact assembly adjacent the point of engagement of the stationary and intermediate contacts, means biasing the movable contact assembly to the open circuit position, the second serially related arc assisting opening motion of the driving piston during high current interruption, and the intermediate contact having a lost-motion mechanical connection with the movable contact assembly.

5. A circuit interrupter of the liquid break type including a casing having an apertured partition member, a relatively stationary rod-shaped contact disposed adjacent one end of the casing, a movable contact assembly movable through the aperture in the partition member and including a hollow piston member through which liquid may flow, an intermediate contact and a driving piston, the rod-shaped stationary contact extending at least part way through the hollow piston member to engage the intermediate contact in the closed circuit position of the interrupter, a rod-shaped movable contact movable through the driving piston to engage the intermediate contact in the closed circuit position, the relatively stationary contact and the intermediate contact being cooperable to establish an arc within the hollow piston member which is subjected to the liquid flow passing through the hollow piston member, the movable contact being cooperable with the intermediate contact to establish a second serially related arc, inlet passage means provided in the movable contact assembly adjacent the point of engagement of the stationary and intermediate contacts, the driving piston being disposed on the other side of the partition member, means biasing the movable contact assembly to the open circuit position, the said second arc assisting the driving piston during high current interruption, and the intermediate contact having a lost-motion mechanical connection with the movable contact assembly.

6. A circuit interrupter of the liquid break type including a casing, a differential piston movable within the casing carrying a movable hollow member of appreciable length therewith through which liquid may flow, a relatively stationary contact extending into the hollow member, a rod-shaped movable contact making engagement with the stationary contact in the closed circuit position, and means biasing the differential piston member to the open circuit position.

7. A circuit interrupter of the liquid break type including a casing having an apertured partition member, a movable differential piston assembly movable through the aperture and carrying a movable hollow member of appreciable length

therewith through which liquid may flow, a relatively stationary contact, a movable contact engaging the stationary contact adjacent the interior of the hollow member, and means biasing the differential piston member to the open circuit position.

8. A circuit interrupter of the liquid break type including a casing having an apertured partition member, a movable differential piston assembly movable through the aperture and carrying a movable hollow member of appreciable length therewith through which liquid may flow, a relatively stationary contact, a movable contact engaging the stationary contact adjacent the interior of the hollow member, means biasing the differential piston member to the open circuit position, the differential piston member having two piston surfaces of unequal area, the casing having on one side of the partition member an enlarged portion and a restricted portion, and the smaller piston surface moving from the enlarged portion into the restricted portion.

9. A circuit interrupter of the liquid break type including a casing, a relatively stationary contact disposed adjacent one end of the casing, a movable contact assembly including a piston, a movable intermediate contact and a driving piston, the movable intermediate contact separating from the relatively stationary contact to establish an arc, the first said piston defining one or more orifices through which said arc is drawn during the opening operation, the opening motion of the first said piston causing flow of liquid through said one or more orifices adjacent said arc, a movable contact disposed adjacent the other end of the casing and cooperable with the intermediate contact to establish a second serially related arc, means utilizing the pressure from the second arc to accelerate motion of the driving piston during high current interruption, and the movable contact having an opening movement in the same direction as opening movement of the intermediate contact.
